CLAIM

The ornamental design for a connector as shown and described.

DESCRIPTION

FIG. 1 is a top, rear perspective view of a connector; FIG. 2 is a bottom, front perspective view thereof; FIG. 3 is an enlarged, right-side elevation view thereof; FIG. 4 is an enlarged, left-side elevation view thereof; FIG. 5 is a top plan view thereof; FIG. 6 is a bottom plan view thereof; and, FIG. 7 is an enlarged, side elevation view thereof, with the connector being used in conjunction with a second, broken line connector in an installed environment.

All broken lines represent structure or features that form no part of the claimed design. Specifically, the dash broken lines form portions of the connector that are unclaimed and/or portions of environmental structure, on which the connector is incorporated or installed, that form no part of the claimed design. The dot-dash broken lines illustrate the boundaries of the connector and form no part of the claimed design.

The appearance of any portion of the connector between the break lines shown in FIGS. 1-2 and 5-6 forms no part of the claimed design.
